UNITED STATES PATENT OFFICE

142,810

DESIGN FOR A BAND SAW OR SIMILAR ARTICLE

Raymond H. Andresen, Chicago, Ill., assignor to Peerless Tool & Engineering Co., a corporation of Illinois

Application June 14, 1945, Serial No. 120,089

Term of patent 14 years

(Cl. D93—3)

To all whom it may concern:

Be it known that I, Raymond H. Andresen, a citizen of the United States and a resident of the city of Chicago, in the county of Cook and State of Illinois, have invented a new, original, and ornamental Design for a Band Saw or Similar Article, of which the following is a specification, reference being had to the accompanying drawing, forming a part thereof.

On the drawing:

Figure 1 is a perspective view of the band saw, or similar article, showing my new design, and

I claim:

The ornamental design for a band saw or similar article, as shown.

RAYMOND H. ANDRESEN.
